UNITED STATES PATENT OFFICE.

JACOB KEENE, OF MIDDLETOWN, NEW YORK.

WIRE-PULLER.

SPECIFICATION forming part of Letters Patent No. 288,241, dated November 13, 1883.

Application filed April 14, 1883. (No model.)

To all whom it may concern:

Be it known that I, JACOB KEENE, a citizen of the United States, residing at Middletown, in the county of Orange, State of New York, have invented a certain new and Improved 5 Wire-Puller, of which the following is an exact specification, to be more fully understood by reference to the drawings, in which--

Figure 1 is a perspective view of my device, 10 and Fig. 2 a detail section on the line 1 2, Fig. 1.

The instrument which I have invented is intended, primarily, to seize and firmly hold wires and similar objects, and may also be 15 used for many of the other purposes for which wrenches and nippers are used.

It consists, essentially, of two levers, A B, one of which, A, has a curved and hooked end, E, and the other, B, has a pivot, e, at its 20 corresponding end, which fits into the hook of the lever A. At their other ends the levers are linked or secured together in the manner shown in the drawings, and are so inclined to each other that power applied to the links in 25 the direction of the levers will tend to draw the levers together, tightly grasping a wire or other object between two pads, a b, on the inner surface of the levers. These pads have roughened surfaces, and are pivoted in the 30 levers, as at e, so as to have a slight rocking motion upon the curved bearing-surfaces of the levers, whereby they will adapt themselves to any surface of the object grasped.

The curved end of the lever A is slotted at 35 d, so as to permit of the passage of the wire, which it is desired to grasp and pull in the direction of its length; and by thus slotting this

lever and pivoting it to the other in a detachable manner I gain in cheapness of construction and in the ease with which the tool can 40 be manipulated. The wire passing through the slot will be guarded thereby from bending in so sharp a manner as to injure its strength.

The operation of the tool and the facility with which it can be used and shifted will be 45 seen from the drawings, where g represents the end of a fence or telegraph wire to be stretched in the direction of the links. Power being applied to the links in the direction of the levers, the greater the strain the tighter 50 will be the grasp, and no bend or angle will be made in the wire.

Without the links the instrument will form a useful tool for hand use.

What I claim is—

1. The wire puller or stretcher consisting of the two detachable second-class levers A B, one of which is slotted and hooked at its bearing end, so as to engage with the pivot e on the other lever and furnish a guide for the 60 wire or other object to be grasped.

2. The wire puller or stretcher consisting of the two second-class levers A B, having the grasping-pads a b, one lever having the slot and hooks, and the other the pivot, and provided with links g at their opposite ends, substantially as described.

3. The slotted, hooked, and pivoted second-class levers A B, provided with the grasping-pads a b, substantially as described.

JACOB KEENE.
